COMBINED SALT-AND-PEPPER SHAKER

Franco Polime, Chappaqua, N. Y., assignor to Twin Bottles, Inc., Port Chester, N. Y., a corporation of New York

Application October 3, 1950, Serial No. 12,441

Term of patent 14 years

(Cl. D44—22)

To all whom it may concern:

Be it known that I, Franco Polime, a subject of the Italian Government, residing at Chappaqua, in the county of Westchester and State of New York, have invented a new, original, and ornamental Design for a Combined Salt-and-Pepper Shaker, of which the following is a specification, reference being had to the accompanying drawings, forming part thereof.

Fig. 1 is a side elevational view of a combined salt-and-pepper shaker, showing my new design;

Fig. 2 is a top plan view of the design shown in Fig. 1; and,

Fig. 3 is an end elevational view of the design shown in Fig. 1.

I claim:

The ornamental design for a combined salt-and-pepper shaker, substantially as shown.

FRANCO POLIME.
